UNITED STATES PATENT OFFICE.

EDDY T. THOMAS, OF NEW YORK, N. Y., ASSIGNOR, BY MESNE ASSIGNMENTS, TO THE ELECTRIC STONE CLEANING AND RENOVATING COMPANY, OF JERSEY CITY, NEW JERSEY.

ELECTRIC SEAM-CALKING TOOL.

SPECIFICATION forming part of Letters Patent No. 634,315, dated October 3, 1899.

Application filed December 4, 1895. Serial No. 571,017. (No model.)

To all whom it may concern.

Be it known that I, EDDY T. THOMAS, a citizen of the United States, and a resident of the city, county, and State of New York, have 5 invented a new and useful Improvement in Electric Seam-Calking Tools, of which the following is a specification.

The object of this invention is to operate seam-calking tools for calking ships by electricity.

The invention consists in operating by an electric motor a spring and cam actuated tool, a cam for compressing the spring and forcing the tool back, a spring for operating 15 the tool forward against the object to be acted upon, adjustable means to give more or less tension to the spring, a cam having one or more elevations to operate the tool one or more times at each revolution of the motor- 20 arbor, horizontal trolley-wires and trolley-wheels for conveying the current to and from the motor, a reel for winding the motor-wires, means to prevent the reel from turning, and the current-wires for conveying the electricity 25 and supporting the motor.

Figure 1 is a side view of the motor, tool, and operating parts. Fig. 2 is a top view of Fig. 1. Fig. 3 is a top view of Fig. 1, having reel attachment. Fig. 4 shows the construction of reel, the position of the negative and positive wires, and motor-conductors. Fig. 5 shows the conductors and reel-supports, and Fig. 6 shows the motor supported by the conducting-wires from the trolley-axle.

35 A in the several figures represents an electric motor provided with an arbor A⁵, journaled at each end of the motor-shell on which the cam B is secured, as shown in Figs. 1, 2, and 3. These motors are of ordinary construction and are to be made very light, 40 weighing from fifteen to twenty pounds, which will enable the operator to readily control the instrument.

A' and A² are handles which enable the operator to easily guide the tool along the object to be treated.

45 A⁹, Figs. 1, 2, and 3, is a switch operated by the button A¹⁰ and is located on the motor to make it convenient for the operator to start 50 and stop the instrument.

A¹¹ and A¹², Fig. 2, are thumb-screws by

which the negative and positive wires from the dynamo or battery are secured to the motor conductors or poles A¹⁴ and A¹⁵.

A', Fig. 1, is a section secured to the motor 55 and drilled through from end to end and supports the tool-holder E, spring C, and screw D. The hole is tapped at its rear end to receive the thread D' of the screw D and has a narrow longitudinal slot A⁸, Figs. 1 and 2, 60 cut through its upper wall, in which the lug E' of the tool-holder E slides back and forth when the machine is in operation.

E, Fig. 1, is a tool-holder having a recess in its outer end in which the shank F' of the 65 tool F fits. It is provided with a lug E', which prevents the holder from turning to the right or left. The lug E' may be dispensed with by using any of the well-known equivalents to prevent the tool-holder from turning and by allowing the free end of the tool-holder to run against the cam B.

B, Fig. 1, represents a cam-flange secured to the motor-arbor A⁵ and has on its inner face an incline plane B³ gradually rising from 75 its lowest face-surface B⁴ until it reaches the drop B'. At each revolution of this cam the incline plane B³ forces the lug E' and the tool-holder E back, compressing the spring C until the drop B' is reached, at which point the 80 spring forces the tool-holder forward and causes the calking-tool F to operate against the edge of the overlapping steel plate to force the edge against the under plate. In order to prevent the lug E' in its forward 85 movement from striking the face of the cam as it springs off the elevation at B', the cam B is set so that the lug E' will strike the end wall A¹³ of the slot A⁸ instead of the cam-surface at B⁴, thereby preventing any injury to 90 the motor-coils. When a heavy blow is necessary to operate the tool F, the spring C is compressed by turning the screw in, and vice versa for a light blow. Should it be found that the tool F does not operate fast enough, 95 two or more elevations B' and B² can be used on one cam, as shown in Fig. 3.

A⁶ A⁶, Figs. 3 and 6, are stanchions secured to the motor A and support the winding-drum arbor H⁶. These stanchions are bored 100 out on their inner sides to receive the conducting-disks H³ and H⁴, Figs. 4 and 5, which

revolve with the drum II and are insulated from the stanchions by the vulcanized-rubber cups II⁵. The inner sides of these stanchions A⁶ are provided with grooves J⁴, as shown in Fig. 5, to receive the conductors or poles A¹⁴ and A¹⁵, Fig. 2, which press against the under side of the disks II³ and II⁴ to complete the circuit.

H, Figs. 3, 4, and 6, is a drum on which the 10 combined conducting and support wires J are wound. It is provided with end flanges II' and II² and is supported by the arbor II⁶. The covered or insulated negative and positive wires J² and J³ are for convenience twisted 15 together, forming one rope or cable J, as shown in Figs. 4 and 6. This cable J is separated as it reaches the drum. The negative part J² is turned to the left and the positive to the right. Both are securely embedded in 20 the drum II and their free ends firmly pressed against the conducting-disks II³ and II⁴, as shown in Fig. 4.

K and K', Fig. 6, are copper trolley-wheels loosely journaled on the axle K⁴ and held in 25 place by nuts K². These copper wheels are provided with grooves K³ around their peripheries, in which the trolley-wires I I' rest. The conducting and supporting cable J, Fig. 6, is separated at its upper end. The negative 30 part J² is turned to the left, while the positive part J³ is turned to the right, and both ends are firmly secured to the axle K⁴ by aid of the friction-clamps J⁵ and J⁶. That the electric current may readily pass from the 35 trolley-wheels to the conductors J² and J³ the clamps J⁵ and J⁶ are set in contact with the sides of the trolley-wheels, as shown in Fig. 6.

II', Fig. 6, is a drum-erank which enables the operator to raise or lower the motor to 40 any desired point, where it is held in place by the friction-screw II⁸ as its inner end presses against the flange II' and acts as a brake.

On the outer side of the cam B a thin metal 45 plate L is secured, as shown in Fig. 3, which acts as a blower to clear the dirt and scales from the work being done.

The operation is as follows: The trolley-wires I and I' are tightly suspended near to and parallel one with the other along the object to be treated and properly arranged to complete the circuit to and from the electric generator. The trolley-truck is then mounted on the wires I and I' and the negative and positive wires J² and J³ secured to the clamps A⁵ and A⁶. 50 The motor is then raised or lowered by turning the crank H⁷ until it is opposite the object to be treated. The motor is then started by closing the circuit with the button A¹⁰ of the switch A⁹. The tool F is then guided 55 along the object to be treated, raised or lowered by turning the crank H⁷, and moved to the right or left by drawing the trolley-truck along the wires I and I'. In case of temporary work and on other occasions the trolley-wires I and I' and trolley-truck may be dispensed with and also the reel by securing portable negative and positive wires direct to the motor, as in Fig. 2, from the dynamo or other suitable wires. 60

By the aid of this device it can be readily seen that calking the seams of ships, boilers, tanks, and like articles can be done with great despatch.

Having thus fully described my invention, 75 what I claim, and desire to secure by Letters Patent, is—

In an electric calking-machine the rotatable arbor A⁵, cam B fixed to the arbor A⁵, and having a fan L, to blow away the dirt and 80 scales, in combination with the tool-carrier E slidably supported and having lug E', in close proximity to cam B, and the spring C, to force the carrier forward as and for the purpose described.

In testimony that I claim the foregoing as my invention I have signed my name, in presence of two witnesses, this 4th day of December, 1895.

EDDY T. THOMAS.
